UNITED STATES PATENT OFFICE

STUART G. BAITS, OF GROSSE POINTE PARK, MICHIGAN, ASSIGNOR TO HUDSON MOTOR CAR COMPANY, OF DETROIT, MICHIGAN, A CORPORATION OF MICHIGAN

MUFFLER FOR INTERNAL COMBUSTION ENGINES

Application filed December 20, 1929. Serial No. 415,486.

My invention relates to mufflers for internal combustion engines and has for its object to provide a new and improved muffler which will not only muffle the exhaust of the engine 5 more efficiently but which will also be less expensive to manufacture and more durable.

As is well known by those skilled in the art mufflers for internal combustion engines will not always perform as well on one type of 10 engine as on another. For instance a muffler which is entirely satisfactory for a six cylinder engine may be much less so when used on a four cylinder engine and vice versa. The muffler embodying the present invention 15 has been found to be particularly satisfactory with six cylinder engines and also gives satisfactory results with straight eight engines.

The muffler embodying my invention can be made very cheaply and rapidly but is 20 strong and can withstand the strains to which it is likely to be subjected due to muffler explosions which occur when unburned gas accumulates in the muffler. The muffler embodying my invention is also capable of being 25 made in different sizes for different sizes and types of engines by changing a single part of the construction.

The invention will be fully understood 30 from the following description when taken in connection with the accompanying drawings, and the novel features thereof will be pointed out and clearly described in the claim at the close of this specification.

Fig. 1 is a longitudinal section of a muffler 35 embodying my invention in its simplest form.

Fig. 2 is a sectional view of a similar muffler intended for use on a larger engine.

Fig. 3 is an end view, and

Fig. 4 is a section taken on line 4-4 of 40 Fig. 2.

Referring particularly to Fig. 1 of the drawings:

The muffler includes an inlet pipe 11, two 45 body end pieces 12 and 13, and four or more perforated baffles 14, 15, 16 and 17. An ex-

haust pipe 18 may also be connected at the rear end.

The two end body members 12 and 13 and the four baffles 14, 15, 16 and 17 are all flanged and arranged with the flanges in contact with each other. The parts are then preferably welded together as for instance by butt or spot welding. Each of the baffles is of spheroidal shape but the baffles 14 and 17 have in addition to their hemispherical portions cylindrical portions which join the laterally extending flanges. The cylindrical portions of these two baffles are pierced by perforations 20 while the spheroidal portions of the baffles 15 and 16 are also pierced by 55 holes 21.

The end body members 12 and 13 are also provided with a plurality of inwardly extending depressions 23 of relatively large extent and depth. These depressions form constrictions in the passage between the baffles 14 and the interior of the end body members and have an influence on the flow of exhaust gases through the muffler. They also increase the resiliency of the shell of the muffler, thus 60 improving its resistance to the strains of muffler explosions, and by modifying the form of the otherwise bell-shaped or generally hemispherical ends, avoid any tendency toward resonance in the latter. 65

The exhaust gases from the engine enter the end body member 12 through the pipe 11, then pass through the constricted passage between the inside of the end body member and the hemispherical baffle 14, then enter 70 the baffle through the holes 20, then pass the second baffle through the holes 21, thus entering the central space 24 of the muffler. Thereafter they pass through the holes in the second set of baffles and finally escape through the 75 exhaust pipe 18. I find in actual practice that the arrangement described produces a very effectual muffling of the exhaust.

In Fig. 2 I have shown my improved 80 muffler constructed for use in connection with 85

a larger engine. In this case the muffler is exactly the same except that the flanges of the end member 30 and baffles 31 and 32 are welded to a flange 33 on a cylindrical body 5 member 34 to the other end of which are welded the baffles 35 and 36 and the body-end member 37. The body member 34 may be made of any desired length, and it will thus be seen that the capacity of the muffler may be 10 easily increased by providing it with a body member of the required length.

I claim:

A muffler for internal combustion engines having an exterior shell, exhaust and inlet 15 pipes connected at the ends thereof, said ends being of general hemispherical form broken by a plurality of inwardly extending depressions, and two oppositely facing groups of baffles within said shell, one of said groups 20 being positioned adjacent the inlet pipe and the other group being positioned adjacent the exhaust pipe, each of said groups comprising an inner and outer baffle having contacting flanges extending to the exterior shell, said 25 inner baffle having a perforated outwardly extending portion of general spherical curvature, said outer baffle having a perforated outwardly extending substantially cylindrical portion connecting an end portion of 30 general hemispherical form.

In testimony whereof I affix my signature.
STUART G. BAITS.
